(57) **CLAIM**

The ornamental design for a modular power system, as shown and described.

DESCRIPTION

FIG. 1 is a front right perspective view of a modular power system showing the new design;

FIG. 2 is a rear right perspective view of FIG. 1;

FIG. 3 is a front view of FIG. 1;

FIG. 4 is a right side view of FIG. 1;

FIG. 5 is a rear view of FIG. 1;

FIG. 6 is a left side view of FIGS. 1; and,

FIG. 7 is a front right perspective exploded view of FIG. 1.

The broken lines shown represent portions of the modular power system that form no part of the claimed design. The shade lines shown represent surface shading and not surface ornamentation, color, or material type.

The wave shaped lines illustrate a symbolic break in length. The appearance of any portion of the article between the break lines forms no part of the claimed design.
